CLOTHES HANGER

Russell D. Finnell, Orange, Tex.

Application February 27, 1946, Serial No. 650,420

2 Claims. (Cl. 223—91)

1

My invention relates to clothes hangers and more particularly to hangers for coats having clamping means thereon to support trousers, slacks, ladies' skirts and the like in vertical position.

The object of my invention is to provide an improved clothes hanger supporting coats, trousers, slacks, skirts and the like in such a manner that garments hung on this improved hanger will keep their shape better and longer, thereby saving time and money.

Other objects of my invention, may appear in the following specification describing my invention with reference to the accompanying drawing illustrating a preferred embodiment thereof. It is, however, to be understood that my invention is not to be limited or restricted to the exact construction and combination of parts described in the specification and shown in the drawing but that such changes and modifications can be made which fall within the scope of the claims appended hereto.

In the drawing:

Figure 1 is a front elevation of the clothes hanger according to my invention.

Figure 2 is a fragmentary end view of Figure 1.

Figure 3 is a sectional view taken on line 3—3 in Figure 1, showing the hanger in open position ready to receive a pair of trousers therein.

Figure 4 is a fragmentary front elevation of the clothes hanger according to my invention having a modified form of shoulder pads thereon.

Figure 5 is an end view of Figure 4.

Figure 6 is a sectional view taken on line 6—6 in Figure 4.

Figure 7 is a view similar to Figure 2 showing the use of a light metal channel as a coat base.

Figure 8 is a fragmentary perspective view of the clothes hanger shown in Figure 1 with a pair of trousers supported by the hanger, and

Figure 9 is a detail showing the blank used to form the modified shoulder pad shown in Figures 4, 5 and 6.

Referring now in detail to the drawing the hanger has a coat base 10 made of any suitable stiff material such as steel, aluminum, wood or plastic. It may be made in various lengths to fit coats of different sizes. It is substantially rectangular but the portions supporting the shoulders of a coat are rounded and provided with shoulder pads 11 made from cardboard or any other suitable material. Two elongated openings 12 are provided in the coat base 10 adjacent its upper edge and its curved shoulder portions.

A garment hanger is supported in the openings 55

2

12 of the base 10, the garment hanger being made from one continuous piece of wire in the following manner: A hook 13 is formed having a downward extending neck 14. From the end of the neck the wire extends laterally and downwardly forming a sloping side member 15. Then the wire extends straight down to provide a straight standing member as shown at 16, the wire from the lower end of the standing member 16 then sloping forwardly and downwardly to form a sloping supporting leg. The wire from the lower end of the supporting leg then extends through one of the openings 12 in the coat base 10 from the rear to the front of the latter and thence is bent horizontally to extend toward and adjacent to the other of the openings 12 in the coat base 10 to form clamping member 17. The wire from the clamping member 17 adjacent the other of the openings 12 in the coat base 10 extends through the latter-named opening from the front to the rear of the coat base and then slopes rearwardly and upwardly to form a second supporting leg, as shown at 18. The wire from the upper end of the second supporting leg 18 extends straight upwardly to provide a second straight standing member, as shown at 19. The wire from the upper end of the second straight standing member 19 extends upwardly and inwardly to form a second sloping side member 20, the end of the wire from the upper end of the sloping side member 20 being then twisted around the neck 14, as shown at 21 in Figure 1.

In order to suspend a pair of trousers or the like on the hanger the wire portion is shoved downwardly through the openings 12 in the coat base 10 so that the straight downwardly extending wire portion 16 and 19 will be in the position shown in Figure 3 creating a comparatively wide open space between the coat base 10 and the clamping member 17 into which the cuffs of a pair of trousers 22 can be inserted easily. Then the wire portion is pulled back into normal position so that the clamping member 17 will engage the cuffs of the trousers forcing them against the front surface of the coat base 10. This front surface is roughened as shown at 23 in Figure 1 decreasing the possibility that the trousers may slip out of the clamping support of the hanger. The weight of the trousers will exert a downward pull on the clamping member 17 which will result in a tighter clamping force between the member 17 and the coat base 10 on account of the shape of the wire portion of the hanger.

The coat hanger may be further improved by attaching the modified shoulder pads 24 shown

in Figures 4, 5 and 6 onto the coat base 10. This pad is preferably made from a cardboard blank of elongated symmetrical octagon shape as shown in Figure 9. Adjacent each of its transverse edges a hole 25 is provided on its longitudinal center line. Intermediate these two holes the cardboard blank is slotted lengthwise and crosswise to form two adjacent tongs 26 which are turned down so that the rounded shoulder portion of the coat base can be received between them. The ends of the blank are rolled under and a rivet 27 extending through the holes 25 in the pad blank and through the coat base 10 holds the pad in place. The tongs 26 are arranged so that the rearward portion of the pads will be larger than the forward portion as clearly shown in the drawing. When a coat is hung on the hanger the weight of the coat will urge the pads 24 into the shoulders to support the coat in the position in which it is worn.

To provide a stronger hanger the coat base can be formed from a lightweight metal channel 28 as shown in Figure 7 on which shoulder pads 29 are fastened.

Having described my invention I claim as new and desire to secure by Letters Patent:

1. In a clothes hanger, the combination with a coat-supporting base having rounded upper corners, there being at least two openings spaced from each other extending through said coat base, of a garment hanger supported in the openings of said base, said garment hanger being formed from a single length of wire and having the upper end terminating in a hook, said wire extending downward from the hook to provide a neck, the wire from the lower end of the neck then extending laterally and downwardly to form a sloping side member, the wire from the lower end of said sloping side member then extending straight downwardly to provide a straight standing member, the wire from the lower end of said standing member then sloping forwardly and downwardly to form a sloping supporting leg, the wire from the lower end of said supporting leg then extending through one of the openings in the coat base from the rear to the front of the latter and thence being bent horizontally to extend toward and adjacent to the other opening in the coat base to form a clamping member, the wire from the clamping member adjacent the other opening in the coat base then extending through the latter-named opening from the front to the rear of the coat base and then sloping rearwardly and upwardly to form a second sloping supporting leg, the wire from the upper end of said second supporting leg then extending straight upwardly to provide a second straight standing member, the wire from the upper end of said standing member then extending upwardly and inwardly to form a second sloping side member, the wire from the upper end of said second side member being then twisted about said neck, the openings in said coat base being of a size such that the coat base normally tends to lower by gravity upon the supporting legs of the garment hanger, whereby a garment may be clamped between the coat base and the clamping member of the garment hanger.

2. In a clothes hanger, the combination with a coat-supporting base having rounded upper corners, there being at least two openings spaced from each other extending through said base, of a garment hanger supported in the openings of said base, said garment hanger being formed from a single length of wire and having the upper end terminating in a hook, said wire extending downward from the hook to provide a neck, the wire from the lower end of the neck then extending laterally and downwardly to form a sloping side member, the wire from the lower end of said sloping side member then extending straight downwardly to provide a straight standing member, the wire from the lower end of said standing member then sloping forwardly and downwardly to form a sloping supporting leg, the wire from the lower end of said supporting leg then extending through one of the openings in the coat base from the rear to the front of the latter and thence being bent horizontally to extend toward and adjacent to the other opening in the coat base to form a clamping member, the wire from the clamping member adjacent the other opening in the coat base then extending through the latter-named opening from the front to the rear of the coat base and then sloping rearwardly and upwardly to form a second sloping supporting leg, the wire from the upper end of said second supporting leg then extending straight upwardly to provide a second straight standing member, the wire from the upper end of said standing member then extending upwardly and inwardly to form a second sloping side member, the wire from the upper end of said second side member being then twisted about said neck, the openings in said coat base being of a size such that the coat base normally tends to lower by gravity upon the supporting legs of the garment hanger, whereby a garment may be clamped between the coat base and the clamping member of the garment hanger.
